UNITED STATES PATENT OFFICE.

SAMUEL STARRETT, OF LONDONDERRY, IRELAND, ASSIGNOR OF ONE-HALF TO THOMAS McCARTER, OF SAME PLACE.

DESIGN FOR A PRINTER'S SIDE-STICK.

SPECIFICATION forming part of Design No. 22,965, dated December 12, 1893.

Application filed September 20, 1893. Serial No. 486,033. Term of patent 14 years.

To all whom it may concern:

Be it known that I, SAMUEL STARRETT, a subject of the Queen of Great Britain, residing at No. 1 Derryview Terrace, Waterside, in the city of Londonderry, Ireland, have invented or produced a new and original Design for a Printer's Side-Stick, of which the following is a full, clear, and exact specification.

The object of this invention is to provide a novel and ornamental sidestick for printers' use; and it consists in a printer's sidestick having parallel faces or edges and concaved longitudinal grooves in its upper and lower sides.

15 The design is illustrated by the accompanying drawings, in which—

Figure 1 is a top plan view of the sidestick; and Fig. 2 is a transverse sectional view of the same to show the grooves in the opposite sides 20 of the sidestick.

Referring to the drawings it will be observed that the sidestick is provided with opposite parallel flat faces or edges *b* and *c*, while the upper and lower sides of the sidestick are provided with longitudinal concaved grooves *d*, the ends of which terminate at some distance from the ends of the sidestick. 25

What I claim is—

The design for a printer's sidestick, substantially as shown and described. 30

In testimony whereof I, the said SAMUEL STARRETT, have hereunto set my hand this 30th day of August, 1893.

SAMUEL STARRETT.
